Fig. 1

Fig. 2

Fig. 3

FIG. 1 is a top plan view of a casserole dish embodying my new design.

FIG. 2 is a side elevational view, with the opposite side view being identical.

FIG. 3 is an end elevational view, with the opposite end view being identical.

The characteristic feature of the design resides in the particular ornamentation applied to the outer sidewall, as shown.

I claim:

The ornamental design for a casserole dish, as shown and described.
